CONTAINER FOR INSECTICIDE SPRAYERS
OR SIMILAR ARTICLES

Samuel A. Halaby, Sr., Kenneth S. Halaby, and Samuel A. Halaby, Jr., all of Rochester, N.Y., assignors to Samuel Halaby, Inc., Rochester, N.Y.

Filed Apr. 13, 1964, Ser. No. 79,445

Term of patent 14 years

(Cl. D31—3)

FIG. 1

FIG. 2

FIG. 3

FIG. 4

FIG. 5

FIG. 6

FIG. 7

FIG. 1 is a front elevation of a container for insecticide sprayers or similar article showing our new design;

FIG. 2 is a side elevation thereof;

FIG. 3 is a top plan view thereof;

FIG. 4 is a rear elevation thereof;

FIG. 5 is a bottom plan view thereof;

FIG. 6 is a cross-sectional view taken on line 6—6 of FIG. 1; and

FIG. 7 is a cross-sectional view taken on line 7—7 of FIG. 1.

The broken line showing of the sprayer unit is for illustrative purposes only.

We claim:

The ornamental design for a container for insecticide sprayers or similar articles, substantially as shown and described.
